UNITED STATES PATENT OFFICE.

FRED I. NELSON, OF CHICAGO, ILLINOIS.

AERIAL TRAMWAY.

No. 839,024.

Specification of Letters Patent.

Patented Dec. 18, 1906.

Application filed April 4, 1906. Serial No. 309,797.

To all whom it may concern:

Be it known that I, FRED I. NELSON, a citizen of the United States, residing at Chicago, in the county of Cook and State of Illinois, have invented certain new and useful Improvements in Aerial Tramways, of which the following is a specification.

My invention relates to a scenic aerial tramway, and particularly to a gravity pleasure-railway of that type having a spiral trackway for the descent of the cars by gravity and in which means are provided for elevating the cars from the lower to the upper terminal of the trackway.

15 The object of the invention is to provide a tramway of this character embodying an improved track and car construction, as well as improved means for transferring the cars to and from the elevator.

20 The invention while primarily designed for large pleasure-railways may also be embodied in toys of the gravity-railway type.

In the accompanying drawings, Figure 1 is a perspective view of a gravity-railway constructed in accordance with my invention. Fig. 2 is a side elevation of one of the cars, showing the track and means for suspending the car therefrom. Fig. 3 is a vertical transverse section on line 3 3 of Fig. 2. Fig. 4 is a 25 vertical section showing the elevator at the lower end of its shaft and a car which has entered the same from the lower end of the track. Fig. 5 is a similar view showing the elevator at the limit of its upward movement and the car arranged to pass onto the upper end of the track for descent. Fig. 6 is a vertical longitudinal section showing the construction and mode of mounting the tilting track-rail in the elevator. Fig. 7 is a detail 30 view of the brake device.

Referring to the drawings, the numeral 1 designates a suitable framework upon which is supported a looped or spiral track 2, having terminals 3 and 4 at its highest and lowest elevations and provided at its lower portion with a depression 5, arranged above an artificial lake 6, into which the passenger-cars dip as they near the terminal 4. The track is of the monorail type, from which the 45 cars are suspended, and is preferably in the form of a channelled rail arranged to provide track-surfaces 7 and 8, said rail being secured at intervals to the framework 1 by depending hanger-arms 9, bolted at their upper ends to the framework and bolted or riveted at their lower ends to the rail, the said lower

end of each hanger being preferably provided with a flange or bracket-piece 10, seated in the channel of the rail and receiving the bolts or rivets.

60 The cars designed to run upon the track-rail may be of any preferred general type and construction, but are preferably composed of a boat-shaped body 11 and a hood or canopy 12, secured together by suitable connecting members 13. Each car is supported by a wheeled carrier comprising a pair of yokes 14, connected at their lower ends by a union-bar 15, secured thereto by eyebolts 16. Suspending-links 17 pivotally connect the 65 eyebolts and connecting members 13 of the car and support the car in such manner as to permit it to swing freely in following the curve of the track. The arms of the yoke are provided at their upper ends with bearings 18 for shafts carrying traction-wheels 19, which run upon the track-surfaces 7 and 8 and are flanged to hold the yoke from lateral movement. The arms of the yoke 70 also receive the ends of a stationary axle 20, extending between the same and on which turn guard wheels or rollers 21, which bear and run upon the under side of the rail 2 and hold the wheels 19 in engagement with the track-surfaces. Each roller 21 is mounted 75 between spacing-sleeves 22, fixed to the axle by set-screws 23.

Arranged adjacent to one end of the framework 1 is a tower 24, in which operates an elevator-car 25, adapted to be raised and lowered by any suitable type of hoisting means, and disposed adjacent to said tower is a platform 26, located at the delivery-terminal 4 of the track, said platform being provided for the convenience of passengers entering and leaving the cars. A standard or post 27 supports the track adjacent said platform, and the lower terminal 4 of the track inclines therefrom to the elevator-shaft to adapt the cars to run from the platform by 80 gravity into the elevator-car.

For convenience in stopping the cars as they successively reach the platform 26 brake mechanism is provided, the same comprising a brake bar or shoe 28, suspended from a 85 bearing 29 on the post or standard by links 30, which adapt the shoe to be swung into and out of engagement with the wheels of the truck or wheeled carrier of the car to bring the same to a state of rest and hold the cars 90 stationary during the discharge and entry of passengers. An operating-lever 31 is ful-

crummed on the beam 28 and pivotally connected with the shoe, as at 32, whereby the latter may be thrown into and out of operation.

Arranged upon the elevator-car 25 is a tilting track-rail 33, upon which the carrier-wheels of each passenger-car are adapted to run and which supports the car while it is being elevated from the lowest elevation 4 to the highest elevation 3 of the track 2. The rail 33 is eccentrically hung from the frame of the elevator-car 25 by an intermediate hanger-link 34, said link being so arranged that the rail 33 is adapted to normally drop by gravity to the inclined position (shown in Fig. 4) to aline with the terminal 4. The limit of movement of the rail 33 is controlled by pivotal end supports arranged on opposite sides of the link 34, each of said supports comprising a slotted link 36, movably connected with a bracket or lug 37 by a connecting pin or bolt 38, having free movement in the slot of the link. The rail 33 is adapted to be tilted to the reverse position (shown in Fig. 5) to adapt the elevated car to travel by gravity therefrom to the upper terminal 5 of the track by a trip-arm 39, secured to the portion 3 and arranged to engage the adjacent end of the rail 33 when the elevator-car reaches the limit of its upward movement. The trip-arm 39 is also adapted to hold the rail 33 in alinement with the track-section 3.

On the track 33 and frame of the car 25 are dogs or detents 40 and 41, the dog 40 being arranged to swing in either direction and to be held from swinging movement in one direction by a pivoted controlling-lever 42, adapted to normally drop by gravity to the position shown in Fig. 4 to hold the dog 41 vertical and to be retracted by a trip-arm 43, fixed to the framework 1, when the elevator-car reaches the limit of its upward movement to free the dog 41. The dog 40 is in the form of a bell-crank lever pivoted to swing toward the central suspending-link 34 and to fold down into the channel of the rail 33 and to be normally held projected in the position shown in Fig. 6 by a spring 44, the outward movement of the dog being limited by a stop-shoulder 45. The dog 40 is thus arranged to swing downward under the pressure of the carrier-wheels of a car when the latter passes from the terminal 4 onto the rail 33 and then to be projected by its spring to normal position to engage one of the rear wheels and prevent the car from running back onto the terminal 4, while the dog 41 is normally held projected by the controlling-lever 42 to engage one of the forward wheels and prevent any possibility of forward movement of the car until it has been elevated to the highest point of the track-rail. When the elevator-car reaches the limit of its upward movement and the rail 33 and lever 42 are respectively engaged by the trip devices 39 and 43, the lever 42 will be retracted and the rail 33 au-

tomatically swung to its reverse inclined position, thus allowing the elevated car to run without interference onto the upper terminal 3 for descent down the track 2.

It will thus be seen that my invention provides a railway of the character described in which simple and effective means are provided for elevating the tram-cars and controlling their entrance to and discharge from the elevating device in a convenient manner and little or no attendant labor; also, that an improved type of track and wheeled carrier is provided to secure a free and easy running of the cars and to adapt them to travel at high speed without danger of derailment.

Having thus described the invention, what is claimed as new is—

1. In an aerial tramway, the combination of a frame having an elevator-shaft, an elevator-car arranged to travel in said shaft, an inclined track supported by the frame and leading indirectly from the upper to the lower end of the elevator-shaft, a suspended tram-car arranged to travel on the trackway, a rail arranged within the elevator-car upon which the tram-car is adapted to run when the elevator is in receiving position, and means for tilting said rail to discharge the car upon the upper portion of the trackway when the elevator-car has ascended to delivery position.

2. In an aerial tramway, a framework and elevator structure, a passenger-station disposed adjacent to the latter, an inclined trackway supported by said framework, said trackway having its upper portion leading to the top of the elevator structure and its lower portion extending past the passenger-station and inclined therefrom to the lower portion of the elevator structure, a car adapted to run upon said trackway, an elevator arranged to travel in said elevator structure to transport the car from the lower to the higher portion of the trackway, and means carried by the elevator for arresting the motion of a car running therein, supporting the car while in transit and discharging the car onto the upper portion of the trackway.

3. In an aerial tramway, a framework, an elevator-tower disposed adjacent thereto, a passenger-station disposed adjacent the base of the tower, a gravity-trackway supported by the framework and having its upper and lower terminals leading respectively from the upper end and to the lower end of the tower, said trackway being inclined from the passenger-station to the tower, an elevator within the tower for transporting the car from the lower to the highest portion of the trackway, and means carried by the elevator for arresting the motion of a car running therein, supporting the car while in transit and discharging the car onto the upper portion of the trackway.

4. In an aerial tramway, a framework in-

cluding an elevator shaft or tower, a spiral trackway extending around the frame and connecting at its upper and lower ends with the upper and lower ends of the tower, an elevator-car arranged to run in the elevator-tower, a suspended car adapted to travel down said trackway, a tilting rail within the elevator-car adapted to receive and support the tram-car, and means for tilting said rail and setting the same into receiving and delivery positions when the elevator-car respectively reaches the lower and upper ends of the elevator-tower.

5. In an aerial tramway, the combination of an elevator-tower, an inclined trackway leading from the top and the bottom portion of the tower, an elevator-car arranged to travel in said tower, a suspended car arranged to travel on said trackway, a support within the elevator for suspending the car therein, means associated with said support for holding the suspended car against movement, and means controlling said support to adjust it to receiving and adjusting positions, when, in the movement of the elevator, the support reaches the lower and upper ends of the trackway.

6. In an aerial tramway, a framework and elevator structure, a passenger-station disposed adjacent to the latter, an inclined trackway supported by said framework, said trackway having its upper portion leading to the top of the elevator structure and its lower portion extending past the passenger-station and inclined therefrom to the lower portion of the elevator structure, a suspended tram-car adapted to run upon said trackway, an elevator-car arranged to travel in said elevator structure to transport the car from the lower to the higher portion of the trackway, a suspended brake device to engage the wheels of the tram-car at the passenger-station, and means carried by the elevator-car for arresting the motion of a car running therein, supporting the car while in transit and discharging the car onto the upper portion of the trackway.

7. A pleasure-railway embodying a supporting-frame having an elevator-tower, a monorail leading in a sinuous path from the upper to the lower portion of the tower, a tram-car suspended to travel upon said monorail, an elevator-car arranged to travel in the tower between the terminals of the monorail, and means within the elevator-car for supporting the tram-car, holding the same in supported position, and automatically discharging said car onto the upper portion of the monorail when the elevator reaches the limit of its upward movement in the tower.

8. In an aerial tramway, a suitably-supported descending track, a car adapted to

travel thereon, an elevator for transporting the car from the lowest to the highest portion of the trackway, and automatically-controlled supporting means carried by the elevator for arresting the motion of a car running therein, supporting the car while in transit and discharging the car onto the upper portion of the trackway.

9. In an aerial tramway, a supporting-frame including an elevator-tower, an elevator-car arranged to travel in said tower, a descending track leading sinuously from the top to the bottom portion of the tower, a tram-car having an elevated carrier to run upon said rail, a passenger-station adjacent the base of the tower, a brake device at said station to engage the wheels of the suspended carrier to hold the tram-car from movement, and means upon the elevator-car to support the tram-car in position therein and automatically discharging said tram-car upon the track-rail when the carrier of the tram-car comes into alignment with the upper terminal of said rail.

10. In an aerial tramway, a suitably-supported descending track, a car adapted to travel thereon, an elevator for transporting the car from the lowest to the highest portion of the trackway, a tilting rail upon the elevator, supports therefor adapted to normally hold said rail in receiving position and to adapt the same to tilt to discharging position, stop means for holding the car upon said rail, and means for automatically tilting the rail to discharging position and retracting said stop means when the elevator reaches the highest point of the trackway.

11. In an aerial tramway, an elevated tower, a track-rail leading centrally from the top to the bottom portion of the tower, a tram-car having an elevated carrier to run upon said track-rail, an elevator traveling within the tower for transporting the tram-car from the lowest to the highest portion of the trackway, a supporting-rail within the elevator-car tiltable to different positions to align with the upper and lower terminals of the track-rail, locking means co-operating with said rail to engage the elevated carrier to hold the tram-car in position while in transit in the elevator, and means for automatically tilting said supporting-rail and retracting the latch mechanism to discharge the tram-car onto the upper terminal of the track-rail when the tram-car reaches the limit of its upward movement in the elevator.

In testimony whereof I affix my signature in presence of two witnesses.

FRED I. NELSON.
